(57) **CLAIM**

The ornamental design of a virtual reality remote controller, as shown and described.

DESCRIPTION

FIG. 1 is a top, right side perspective view of a virtual reality remote controller showing the new design.

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The drawings include shade lines that show contour and not surface indicia.

1 Claim, 2 Drawing Sheets
